INVENTOR.

John Kirby Jr.

UNITED STATES PATENT OFFICE.

JOHN KIRBY, JR., OF DAYTON, OHIO, ASSIGNOR TO THE UNITED STATES HEAD-LIGHT COMPANY, OF BUFFALO, NEW YORK, A CORPORATION OF NEW YORK.

FOCUSING DEVICE.

1,298,964.

Specification of Letters Patent.

Patented Apr. 1, 1919.

Application filed October 23, 1918. Serial No. 259,316.

To all whom it may concern:

Be it known that I, JOHN KIRBY, Jr., a citizen of the United States, residing at Dayton, in the county of Montgomery and 5 State of Ohio, have invented a certain new and useful Improvement in Focusing Devices, of which the following is a specification.

My invention relates primarily to electric 10 headlights and has for its purpose to provide mechanism for adjusting the filament of an incandescent lamp to the focal point of a parabolic reflector, as set forth in my pending applications, Serial Number 249-, 15 383, filed August 12, 1918, Serial Number 251,913, filed August 29, 1918, Serial Number 253,678, filed September 12, 1918, and Serial Number 258,254, filed October 15, 1918, from all of which my present invention 20 differentiates in certain particulars not described, or claimed in any of the said applications and which will be made clear in this specification and pointed out in the claims at the end thereof.

One object of my present invention is to 25 provide a focusing device of the spherical type which, by reason of its compactness, reduces the amount of space required for its installation and operation at the rear of 30 the reflector; another object being the construction of such a device with special reference to reducing its weight to a minimum commensurate with requisite strength, and a further object is to combine in such a 35 device maximum efficiency and durability with simplicity, ease of manipulation and minimum cost to manufacture. Other objects and advantages of the invention will appear from the specification which follows.

In headlights of the type to which my 40 invention is applicable it is essential that the center of illumination be located with accuracy in respect of the focal point of the reflector and to this end my invention consists 45 in the novel construction and combination of parts hereinafter more fully set forth and claimed.

The invention is illustrated in the accompanying drawings, which constitute a part 50 of this specification and in which Figure 1 is a side view showing the device assembled and mounted in its position with relation to

the reflector, the same being shown partly in full and partly in section; Fig. 2 is a rear view of the same, the reflector, the supporting ring and a portion of the reflector stand being eliminated; Fig. 3 is a perspective view of the spherical element, formed of sheet metal, as shown in Fig. 1, minus its inner wall; Fig. 4 is a perspective view 60 of the cylindrical sleeve which forms the inner wall for the element shown in Fig. 3 and the sleeve extension therefor; Fig. 5 is a vertical sectional view through the center of the spherical element, which is shown 65 as comprising a casting with the cylindrical sleeve shown in Fig. 4 constituting the inner wall and the sleeve extension, and Fig. 6 is a perspective vertical sectional view through the center of the spherical element and the sleeve extension, and in which these parts are represented as a single structure.

Like reference numerals indicate corresponding parts throughout the drawings. 75

1 represents a portion of a parabolic reflector, the front end of which may be mounted upon any suitable slide or base, as at 2, in the usual manner, a ring 3 is secured to the rear of the reflector, the apex of which is cut away at 4 leaving an opening in the reflector corresponding to the inner diameter of the ring 3. At the bottom of and preferably integral with the said ring 3 there is a laterally disposed arm or 80 bracket 5 having a perforation through which passes an exteriorly screw threaded stem 6 provided with upper and lower adjusting nuts 7, 8, by which the said stem can be adjusted, vertically, in mounting the 85 device, a spring washer 9 being employed to prevent shifting of the parts after being properly set. Depending from the bottom of the stem 6 there is a reduced exteriorly screw threaded stem 10 which passes 90 through a perforation in a boss 11 at the upper end of a standard 12, secured to the base 2, adjusting nuts 13, 14 providing means by which the rear end of the reflector 95 may be properly adjusted.

The upper end of the stem 6 is provided with an enlarged head 15, which is cupped to receive and to which there is securely attached a retaining band 16, having the con-

tour of and forming a support for a spherical element 17, the said band being separated, crosswise thereof, at 18. This band is preferably formed out of sheet metal 5 which, being hard, is adapted to be sprung open sufficient to allow the spherical element 17 to be inserted therein, and when so placed within the band the latter may be caused to embrace the said element tightly 10 by means of a thumb screw 19 having a rounded shoulder 20; a smooth portion 21 and a screw threaded portion 22, the latter engaging a screw threaded lug 23, secured to the band adjacent its point of separation, and the said smooth portion operating through a clearance perforation in a lug 24 secured to the band opposite the lug 23, the rounded shoulder 20 impinges the outer face of the lug 24. Thus by turning 15 the thumb screw in one direction the said element will be grasped tightly by and held securely within the band, and by turning it in the opposite direction the grip on said element will be relieved and the same will 20 then be free to be moved, spherically, within the band.

Referring particularly to Fig. 1 of the drawings, which illustrates the preferred embodiment of my invention, the spherical 30 element 17 is of sheet metal spun, or otherwise formed, to the contour of a portion of a sphere and having a central opening 25 therethrough, as more clearly shown in Fig. 3. Within this opening fits a portion of a 35 cylindrical sleeve 26, which forms a wall for the opening through the said element, which, when thus assembled, may be said to constitute a hollow shell. The sleeve 26 is swaged to form a bead 27 therearound, and 40 after being inserted in place its front end is lapped over the adjacent edge of the element 17, as shown at 28, so that the element is held firmly between the bead 27 and the flange 28, the joints so formed are then soldered and a light, strong structure is thus 45 created. That portion of the sleeve 26 which extends to the rear of the bead 27 may be termed a sleeve extension 29 of the element 17, and the complete cylinder constitutes a 50 receptacle for a lamp socket 30, which is movable longitudinally therein by means which will presently be described.

In order to prevent movement of the lamp 55 socket in any direction except longitudinally of the opening in which it is located, oppositely disposed slots or guide-ways 31 are formed in the wall of the opening in which the socket is movable, these guide-ways being traversed by guide-pins 32, which project from the socket; one such guide-way and guide-pin may, however, suffice but I consider two, as shown, to be more effective. At the rear of the lamp socket there is a reduced, laterally disposed, exteriorly screw

threaded member 33, upon which is mounted and which co-operates with a correspondingly screw threaded disk or wheel 34, the latter being rotatively connected with the sleeve extension 29 by means of a plurality of screws or rivets 35, the heads, 36, of which overlap an inwardly turned flange 37 formed on the sleeve extension 29. The wheel 34 has an extended portion 38, which forms a circumferential shoulder 39, corresponding substantially with the thickness and the inner 75 diameter of the flange 37, and which in conjunction with the rivet heads forms a guideway which is revoluble about the fixed flange 37, from which separation may be accomplished by removing the rivet heads. It 80 will thus be apparent that by turning the wheel 34 in one direction the engaging screw threads will cause the socket 30 to move forward and by turning it in the opposite direction the socket will move backward. 85

It is to be understood that when the device is assembled and mounted in position in the headlight but little adjustment will be required, to accomplish which the operator, with one hand, loosens the thumb screw 19 90 and then moves the spherical element about in its retaining band, or moves the socket forward or backward as may be necessary to bring the lamp filament 40, inclosed in a glass bulb, 41, in proper relation to the focus 95 of the reflector, the same being designated at X.

In order to prevent the spherical element from moving about too freely in the retaining band when its grip on the said element is relieved, by turning the thumb screw 19, the stem 6 is provided with a vertical chamber 42, which also extends through and is in open communication with the inside of the retaining band, and located within this chamber there is a coiled spring 43, one end of which bears against the bottom of the chamber while its opposite end bears against the under side of a movable block 44 having its upper end cupped to the contour of the outer surface of the element 17 and against which the said block is forced by the pressure of the spring, thereby causing a steady movement of said element during the operation of adjustment thereof, and also serving 110 the further purpose of retaining the element in its adjusted position until it is finally secured by tightening the band, in the manner previously described. 115

To provide means by which the socket, while fitting freely in its receptacle, may be restrained from undue movement therein, caused by jarring, or vibration which might affect its propelling mechanism, namely, the wheel 34, one or more springs 45, four of which are shown, may be located in the wall 120 of the socket receptacle arranged to bear against the socket to exert sufficient pressure 125

thereon to require manual effort to turn the wheel. In Figs. 4 and 5 these springs are illustrated as being formed integral with the cylindrical sleeve 26, by shearing, as best 5 shown in Fig. 4, while in Fig. 6 recesses 46 are shown as being formed in the wall of the receptacle, in which recesses separate springs may be secured and caused to perform the same function. Figs. 5 and 6 illustrate modifications 10 in the manner of constructing and combining the spherical element and sleeve extension, Fig. 5 showing the element itself as being solid instead of hollow as shown in Figs. 1 and 3, the cylindrical sleeve of Fig. 15 4 constituting the wall of the socket receptacle, as shown in Fig. 1, while in Fig. 6 the spherical element and sleeve extension are shown as being cast or otherwise formed integral and forming the wall of the socket receptacle.

It will be obvious that either of the modified structures shown in the drawings and described herein may be employed without departing from the spirit of my invention, 25 also that other modifications may be made in respect of minor details and still be within the scope thereof.

What I claim and desire to secure by Letters Patent is:

30 1. In a device of the character described, the combination of a spherical element having a central opening therethrough and constituting a support and guide for a lamp socket without the intervention of other elements, a sleeve fixed to said spherical element and forming a laterally disposed extension thereof, a lamp socket movable in and longitudinally of said opening, a retaining band encircling and constituting a 35 support for said spherical element, means by which said band may be caused to contract and expand to tighten and loosen said spherical element therein, and means carried by said sleeve adapted to control the 40 movement of said socket.

45 2. In a device of the character described, the combination of a spherical element having a central opening therethrough and constituting a support and guide for a socket holder without intervention of other elements, a sleeve fixed to said spherical element and forming a laterally disposed extension thereof, a lamp socket movable in and longitudinally of said opening, a retaining band encircling and constituting a support for said spherical element; said band being susceptible to spring action, means by which said band may be caused to contract and expand to tighten and loosen 50 said spherical element therein, and means carried by said sleeve adapted to control the movement of said socket.

60 3. In a device of the character described, the combination of a spherical element hav-

ing a central opening therethrough and constituting a support and guide for a lamp socket without the intervention of other elements, a sleeve fixed to said spherical element and forming a laterally disposed extension thereof, a retaining band encircling and constituting a support for said spherical element, means by which said band may be caused to contract and expand to tighten and loosen said spherical element therein, a lamp socket movable in and longitudinally of said opening, a toothed reduced member extending rearwardly from said socket, and means carried by said sleeve adapted to engage said toothed member to control the movement of said socket.

4. In a device of the character described, the combination of a spherical element having a central opening therethrough and constituting a support and guide for a lamp socket without the intervention of other elements, a sleeve fixed to said spherical element and forming a laterally disposed extension thereof, a retaining band encircling and constituting a support for said spherical element, a lamp socket movable in and longitudinally of said opening, a reduced exteriorly screw threaded member extending rearwardly from said socket, and mechanism rotatively connected with said sleeve extension having an interiorly screw threaded portion coöperating with said exteriorly screw threaded member whereby said socket may be moved forward and backward in said opening.

5. A new article of manufacture consisting of a component part of a focusing device for electric headlights, comprising a spherical element having a sleeve extension thereon and an opening adapted to receive a lamp socket, said spherical element consisting of a hollow sheet metal shell the inner wall of which is extended beyond the said element to form the said sleeve extension.

6. A new article of manufacture consisting of a component part of a focusing device for electric headlights, comprising a spherical element having a sleeve extension thereon and an opening adapted to receive a lamp socket, said spherical element consisting of a hollow sheet metal shell the inner wall of which is extended beyond the said element to form the said sleeve extension, said sleeve extension having a flange adapted to coöperate with mechanism for moving the said socket forward and backward in said opening.

7. A new article of manufacture consisting of a component part of a focusing device for electric headlights, comprising a sheet metal cylindrical sleeve adapted to form the wall of a lamp socket receptacle and having an inwardly turned flange at one

end thereof adapted to coöperate with mechanism for propelling a lamp socket in said receptacle, said sleeve being provided with springs formed integral therewith and being
5 adapted to exert pressure against the lamp socket.

In testimony whereof, I affix my signature

in the presence of two witnesses this 21st day of October, 1918.

JOHN KIRBY, JR.
